UNITED STATES PATENT OFFICE.

ANTON HOGENSON, OF CALMAR, IOWA.

PIPE-LIFTING MACHINE.

SPECIFICATION forming part of Letters Patent No. 697,719, dated April 15, 1902.

Application filed November 15, 1901. Serial No. 82,423. (No model.)

To all whom it may concern:

Be it known that I, ANTON HOGENSON, a citizen of the United States, residing at Calmar, in the county of Winneshiek and State of Iowa, have invented certain new and useful Improvements in Pipe-Lifting Machines; and I do hereby declare the following to be a full, clear, and exact description of the invention, such as will enable others skilled in the art to which it appertains to make and use the same.

My invention relates to mechanism for lifting pipes or rods from wells, and has for its object to provide a device of this kind which will lift a pipe or rod with a minimum amount of exertion.

With this object in view my invention consists in the novel construction of my clutches.

My invention also consists in the novel construction of the pipe-lifter frame.

My invention also consists in the novel manner of guiding the pipe while the same is being lifted from or lowered into a well.

My invention also consists in certain other novel features of construction and in combination of parts, which will be hereinafter fully described, and specifically pointed out in the appended claims.

Referring to the accompanying drawings, Figure 1 is a perspective view of the pipe-lifter in an operative position. Fig. 2 is a perspective view of one of the pipe-clutches. Fig. 3 is a perspective view of the pipe-catch; and Fig. 4 is a detail view of the lifting-lever, guiding-rollers, and brackets.

Like numerals of reference indicate the same parts throughout the several figures, in which--

1 is the pipe-lifter, composed of a frame 2, substantially like an inverted U, and constructed, preferably, of angle-iron.

3 indicates the bases, having suitable supports 4.

5 is a double lifting-lever centrally fulcrumed to a bracket 6, which is securely bolted or riveted to the frame 2 and also to a cross-support 7 of angle-iron. 8 indicates a bracket which is bolted or riveted to said cross-support and which is secured to said bracket 6 by means of a pin, which pin forms a fulcrum for the double lifting-lever. I provide the bracket 6 with two perforations or

is inserted, said guide-rod resting upon the brace 7 of angle-iron.

12 indicates the guide-rollers, which are journaled on pins 13, secured in the bracket 8. Said guide-rollers are of a peculiar construction and increase in circumference toward their back. The peripheries of said rollers almost contact with each other at their rear ends, while a considerable space is left between the peripheries of the rollers at their forward point, so as to allow the pipe to enter between said rollers.

14 indicates the clutches, consisting of sections 15 and 16. Said section 16 is of a considerable shorter length than section 15 and is provided at its inner end with a hook 17, which extends across and over the shank of said section 15. Said sections 15 and 16 are connected at their outer ends by means of a threaded pin 18, which is pivoted to section 16 and threaded in section 15. Said sections 15 and 16 are so constructed that when they are in a closed position a circular hole or opening 19 is formed between the same, within which the pipe 20 is inserted.

21 indicates the connecting-rods which connect the pipe-clamps with the double lifting-lever. It will be noticed that I provide a series of holes in said lever, within which said connecting-rods may be inserted for the purpose of increasing or diminishing the lift of the clutches or clamps. It will also be noticed that the connecting-rods 21 are of a different length, as one clamp or clutch may most always be below the other, as will be hereinafter fully described.

22 indicates the pipe-catch, which is provided with a circular opening 23. Said pipe-catch is placed on the guide-rod 11 for the purpose of holding a pipe-section in an upright position in order to uncouple the inner tube or pipe. At the top of said guide-rod I provide a suitable guide 24, constructed, preferably, like a split ring, and as the pipe is lifted from the well it is guided into said guide and securely holds the pipe in an upright position.

Having thus fully described the several parts of my invention, its operation is as follows:

When it is desired to raise a pipe from or lower a pipe into a well, the clamps or clutches

are opened by means of raising the clamp-section 16, as shown in dotted line in Fig. 2, so that the hook at the end thereof is disengaged from the shank of section 15. Said 5 clamps or clutches are then closed around the pipe to be lowered or raised. One clamp or clutch is below the other, as shown in Fig. 1. When the handle of said lifting-lever is lowered, the clamp or clutch on the other side 10 of the fulcrum is raised and the clamp or clutch between the fulcrum and the handle is lowered, as is obvious. This throws the entire weight of the pipe upon the clamp or clutch that is being raised and the edges of 15 the circular opening of said clamp or clutch gripping the pipe and raising the same. When, however, the handle of the lifting-lever is raised, the clamp or clutch between the handle and the fulcrum is also raised, and 20 the clamp or clutch on the other side of the fulcrum is lowered. In this instance the weight of the pipe is shifted on the clutch nearest the handle, and as said clutch rises it lifts the pipe. The other clutch being lowered 25 at the same time is now in position to take its turn when the lever-handle is again lowered. Said pipe is at first being raised between the rollers 12, and by reason of their peculiar construction, as before described, said pipe 30 is always in contact with said rollers so long as the same is in position. I have arranged my guide-rod so that the same is not exactly perpendicular; but it inclines forwardly, so that the guide at the top thereof is directly 35 over the guide-rollers 12. When one of the pipe-sections is clear of the guide-rollers, the same is uncoupled and the end thereof rests on the pipe-catch 22. In this manner the lifted pipe-sections can be uncoupled, and the inner 40 tube or pipe can also be uncoupled without the assistance of an extra hand. I have found that the openings in said pipe clamps or clutches are much more efficient when made round than when made square, as said clamps or clutches 45 can be made to fit different-size pipes much more readily and with much better results than when said openings are square. When it is desired to increase or diminish the size of the openings in said clamps or clutches, the 50 shorter section 16 is revolved on section 15 in such a manner as to thread or unthread the pin 18, which is pivoted to section 16. When it is desired to diminish the opening

in said clamp or clutch, said threaded section is turned so as to thread the pin 18 into the 55 longer section 15, and when it is desired to increase the opening in said clutches the threaded section 16 is turned in the opposite direction. I have also found that the pipe-guide rollers 12 are of great assistance when 60 raising a pipe from a well, as the tendency of a pipe when in an upright position is to lean one way or the other. This causes a binding upon the guide at the top of the guide-rod and also causes a binding upon 65 any other guide that may be located at any other point on the machine. The peculiar construction of the guide-rollers makes it possible for said pipe to lean backwardly or to either side and obviates any binding of the 70 pipe or rod with the pipe-guides. They will also guide pipes of different sizes and diameters without any adjustment. When it is desired to lower a pipe into a well, said sections are closed about the pipe, as described, 75 before operating the lever, as first one clutch and then the other is lightly slid up the pipe, which throws the weight on the opposite clutch and allows the pipe to descend.

What I claim as new, and desire to secure 80 by Letters Patent of the United States, is—

1. In a pipe-lifting mechanism, the combination of an inverted-U-shaped frame, brackets secured thereto, a guide-rod secured in one of said brackets, and a lifting-lever fulcrumed between said brackets, guide-rollers journaled in front of said lifting-lever, said rollers increasing in circumference toward their rear ends, whereby the pipe is supported at its rear and sides, clamps or clutches connected to said lifting-lever, substantially as described. 85

2. In a pipe-lifting mechanism, the combination with a frame, and pipe-lifting means of guide-rollers secured to said frame; the 95 rear ends of said rollers being greater in diameter than the front ends, whereby pipes of a different diameter may be accommodated by said rollers substantially as described. 90

In testimony whereof I affix my signature 100 in presence of two witnesses.

ANTON HOGENSON.
